WILLIAM H. BOWLES, OF MEADOW CREEK, WEST VIRGINIA, ASSIGNOR OF ONE-THIRD TO W. H. BOWLES AND SONS, A PARTNERSHIP, ONE-THIRD TO MARSHALL BOWLES, AND ONE-THIRD TO R. G. NUNLEY, ALL OF MEADOW CREEK, WEST VIRGINIA.

RAIL JOINT.

Application filed May 11, 1926. Serial No. 108,337.

My invention relates to improvements in rail joints, and it consists in the combinations, constructions and arrangements herein described and claimed.

5 An object of the invention is the provision of a simple, reliable and stable rail joint which affords facilities for connecting the meeting end portions of two aligned rails and for holding the connected together meeting end portions of the rails against relative movements and particularly against sagging at the joint.

10 A further object of the invention is the provision in a rail joint of a coupling and supporting member which can be secured quickly and easily to the meeting end portions of two aligned rails in position to connect and support the meeting end portions of the rails without the use of the usual fish 15 plates and the usual connecting bolts.

Other objects and advantages of the invention will be apparent from the following description, considered in conjunction with the accompanying drawings, in which

20 Figure 1 is a perspective view of the improved rail joint,

Figure 2 is a section substantially along the line 2-2 of Figure 1,

25 Figure 3 is a section substantially along the line 3-3 of Figure 1.

The improved rail joint comprises a coupling member which is formed by casting or in any other suitable known manner in a single piece and which comprises a base 30 portion 1 having a flat bottom face as indicated at 2. The base 1 has a width considerably greater than that of the base flanges of adjacent aligned rails 3 and has a length considerably greater than the normal distance between two adjacent rail supporting 35 ties 4 so that the base 1 is adapted to extend across the space between said adjacent ties 4 and end portions of the base 1 of considerable length will be supported on said adjacent ties.

40 The coupling member also includes a body which is integral with the base and which extends longitudinally of the base intermediate the side edges of the latter. This body is 45 bifurcated longitudinally for its entire length

by a channel which is substantially of inverted T-shape in cross section and which comprises a vertical upper portion 5 and a horizontal lower portion 6. The furcations of the body thus may be said to constitute 55 retaining side members which have been designated 7 and it is to be observed that the vertical upper portion 5 of the channel in the base is located intermediate the outer side faces of the retaining portions 7 of the 60 body. The channel 5-6 constitutes a seat in which the web and base flange portions of the meeting end portions of the rails 3 are adapted to fit, the base flanges of the 65 meeting end portions of said rails fitting snugly in the horizontal portion 6 of the channel and the web portions of the rails extending in the portion 5 of the channel slightly above the level of the upper end of the portion 5 of the channel so that the upper edge portions of the side retaining members or furcations of the body will fit snugly at 8 under the rail heads at opposite sides of the web portions of the rails. The inner 70 faces of the furcations 7 of the body may be machined or otherwise formed longitudinally intermediate their upper and lower edges so as to produce longitudinally extending shallow grooves 9 which are concavely curved in vertical section and which are provided to reduce the friction between the inner faces of the furcations 7 of the body and the web portions of the rails 3 when the meeting end portions of such rails are slid into the channel 5-6 from opposite 75 ends of the latter to positions to abut or to be close to each other at the approximate transverse medial line of the body. It is to be observed, however, that the inner faces of the upper and lower edge portions of the 80 furcations 7 of the body are in contact with opposite side faces of the web portions of the meeting end portions of the rails.

The furcations 7 of the body may be reduced in thickness externally from their upper edges for part of the height of the body as indicated at 10 to afford ample clearance for the flanges of wheels (not shown) which may traverse the rails. The shoulders which are provided at the lower ends of the 85 100

portions 9 of the furcations of the body slope toward their outer edges as indicated at 11 and the lower portions of the outer faces of the furcations 7 of the body also are formed to slope toward their lower edges and may be concavely curved in vertical sectional configuration as shown at 12 so that moisture which may be deposited on the outer faces of the furcations 7 of the body 10 will drain freely therefrom.

The end portions of the furcations 7 of the body are provided with aligned transverse openings 13 and the web portions of the rails 3 are provided with transverse openings 14 in positions to register with aligned openings 13 when the meeting end portions of the rails are in position to closely approach or abut each other in the channel 5—6 of the body of the coupling member 20 of the device. Retaining pins 15 extend through aligned openings 13—14—13 and are held against axial displacement in any suitable known manner, as by means of cotter pins 16 which extend through transverse openings in the end portions of the pins 15. These cotter pins may be received in lateral pockets, as at 16', in the outer faces of the furcations 7 of the body of the coupling member. When the pins 15 are in place, the 30 rails 3 will be held against any appreciable longitudinal movement relatively to each other although the openings 14 preferably are sufficiently larger in diameter than the pins 15 and the rails 3 preferably terminate 35 slightly apart at their adjacent ends to permit longitudinal expansion and contraction of the rails in response to temperature changes will be permitted.

The furcations 7 of the body of the coupling and supporting member of the device are provided on their outer faces intermediate their ends with integral outwardly and downwardly extending lugs 17 having sloping upper faces. The lower portions of these lugs 17 may be drilled or partially cut away in a direction parallel to the rails to provide notches or seats as indicated at 18 and 19 respectively for the reception of the middle portions of the usual rail bond wires 40 and 21, respectively which connect the rails 3. Ordinarily, rail bond wires 20 and 21 will be provided only at one side of the connected together portions of the rails 3. The lugs 17 are provided on both the furcations 7 of the body of the coupling member of the device so that the rail bond wires 45 may be provided at either of opposite sides of the connected together portions of the rails or the coupling member may be reversed end for end without there being any necessity of changing the location of the usual rail bond wires. The end portions of the rail bond wires may be connected with the rails 3 by means of plugs 22 which are 50 secured in transverse openings 23 in the web

portions of the rails 3 and which have longitudinally extending grooves in which the end portions of the rail bond wires are partially received, thus tending to retain the end portions of the rail bond wires in place 70 in the transverse openings 23 of the rails, although in actual practice, the end portions of the rail bond wires also will be secured to the plugs 22 in any suitable known manner, as by means of solder or by welding. 75

The base 1 of the coupling member of the device is provided with notches 24 in its side edges. The shanks of rail spikes 25 are driven through the notches 24 in the portions of the base 1 which overlie the adjacent ties 4 into said ties so that the heads of the rail spikes will clamp the base 1 firmly to the ties 4. 80

From the foregoing description of the various parts of the device, the operation thereof may be readily understood. The adjacent end portions of adjacent aligned rails are slid to place in the longitudinal channel 5—6 of the body of the coupling member and are connected with the body of the coupling member by means of the pins 15. The coupling member is secured firmly to the ties 4 by means of the rail spikes and the adjacent end portions of adjacent rails will be held securely against any appreciable relative movements and against sagging at the joint between the rails. The meeting end portions of the rails are reinforced by the coupling member and cannot move out of line with each other either vertically or in any other direction without breaking the coupling member or the connections between the coupling member and the rails. The strength of the coupling member is sufficient to resist any stresses to which it is likely to be subjected in service without breaking and an extremely strong and reliable joint thus is produced between adjacent aligned rails. 90

Obviously, the invention is susceptible of embodiment in forms other than that which is illustrated in the accompanying drawings and I therefore consider as my own all such modifications and adaptations thereof as fairly fall within the scope of the appended claims. 105

I claim:

In a bond protecting rail joint, a base adapted to extend underneath adjacent end portions of two adjacent aligned rails and adapted to be fastened to ties, a pair of retaining members integral with said base and extending longitudinally on the base against opposite faces of the adjacent end portions of said rails, said retaining members having aligned transverse openings, concave inner faces, shoulders on the upper portions of the outer faces and concave slopes below said shoulders, a plurality of pockets open at their top edges around the transverse openings in the joint, a raised 115 120 125 130

middle portion of the sloping outer sides, eave pieces extending therefrom, said pieces being channeled on their under sides, pins extending through the transverse openings

5 of the joint and those of the rails, retaining means on the ends of said pins, adapted to

hold one or more electrical bond wires extending from the end of one rail to the end of the other rail by means of channels under the said eave pieces.

WILLIAM H. BOWLES.
